CLAIM

The ornamental design for a gift wrap with ruffled ends, as shown and described.

DESCRIPTION

FIG. 1 is an upper view in perspective of a gift wrap with ruffled ends.

FIG. 2 is a top view of the article of FIG. 1.

FIG. 3 is an end view of the article of FIG. 1, the perimeter of the opening in broken lines forming no part of the claimed invention.

FIG. 4 is a side view of the article of FIG. 1.

FIG. 5 is a perspective view of the article of FIG. 1 in an exemplary use on a cylindrical package, the package in broken lines forming no part of the claimed invention; and, FIG. 6 is a perspective view of the article of FIG. 1 in an exemplary use on a rectangular package, the package in broken lines forming no part of the claimed invention.

In the drawings, the broken lines show portions of a gift wrap and a package that form no part of the claim.

The gift wrap with ruffled ends is shown with a symbolic break in its midsection. The appearance of any portion of the article between the break lines forms no part of the claimed design.
